DESSERT DISH

Henry Albert Holzwarth, Bayside, N.Y., Charles Lewis Metzler, Alpine, N.J., and John Duncan Wark, Freeport, N.Y., assignors to American Can Company, New York, N.Y., a corporation of New Jersey

Filed Apr. 21, 1964, Ser. No. 79,625

Term of patent 14 years

(Cl. D44—10)

Fig. 1.

Fig. 4.

Fig. 2.

Fig. 3.

FIG. 1 is a top plan view of a dessert dish showing our new design;

FIG. 2 is a side elevational view;

FIG. 3 is a bottom plan view; and

FIG. 4 is an enlarged vertical, sectional view taken substantially along line 4—4 of FIG. 1.

We claim:

The ornamental design for a dessert dish, substantially as shown.
